CLAIM

The ornamental design for a snorkel mask, as shown and described.

DESCRIPTION

FIG. 1 is a front elevational view of a snorkel mask showing my new design;

FIG. 2 is a rear elevational view thereof;

FIG. 3 is a left side view thereof, shown at a reduced scale;

FIG. 4 is a right side view thereof, shown at a reduced scale;

FIG. 5 is a top plan view thereof;

FIG. 6 is a bottom plan view thereof;

(Continued)

FIG. 7 is a perspective view thereof;
FIG. 8 is a second perspective view thereof;
FIG. 9 is a third perspective view thereof;
FIG. 10 is a fourth perspective view thereof; and,
FIG. 11 is a fifth perspective view thereof.

1 Claim, 11 Drawing Sheets
